COUPON

Samuel Shore, Providence, R. I., assignor to United Public Markets, Inc., a corporation of Rhode Island

Application April 7, 1954, Serial No. 29,900

Term of patent 3½ years

(Cl. D59—6)

To all whom it may concern:

Be it known that I, Samuel Shore, a citizen of the United States, residing at Providence, State of Rhode Island, have invented a new, original, and ornamental Design for a Coupon, of which the following is a specification, reference being had to the accompanying drawing, forming a part hereof.

In the drawings,

Fig. 1 is a top plan view of a coupon showing my new design; and

Fig. 2 is a bottom plan view thereof.

I claim:

The ornamental design for a coupon, as shown.
